His Attorney.

UNITED STATES PATENT OFFICE.

GEORGE W. BOWER, OF SCHENECTADY, NEW YORK, ASSIGNOR TO GENERAL ELECTRIC COMPANY, A CORPORATION OF NEW YORK.

TROLLEY SWITCH.

Application filed March 25, 1922. Serial No. 546,804.

To all whom it may concern:

Be it known that I, GEORGE W. BOWER, a citizen of the United States, residing at Schenectady, in the county of Schenectady, State of New York, have invented certain new and useful Improvements in Trolley Switches, of which the following is a specification.

The present invention relates to electric street car systems and more especially to systems of the trackless trolley type.

On account of the absence of the usual grounded track in trackless trolley systems, it is necessary to provide a double overhead trolley wire arrangement for the supply and the return sides of the power circuit respectively and to provide the car with double contact means for collecting and returning the current from and to the respective wires.

The object of my invention is to provide improved switch means whereby a double contact trolley device may pass freely and quietly from a main line of double overhead wires to a branch line, or vice versa, and without danger of short circuiting from one wire to the other.

One form of embodiment of the invention is shown in the accompanying drawing, in which Fig. 1 is an under side plan of the switch with ends of the trolley wires shown attached thereto; Fig. 2 is an isometric perspective view thereof, and Fig. 3 is a similar view of the contact end of a current collector adapted for use in such a system.

The current collector shown in part in the drawing is the subject of another application Serial No. 516,094, filed November 18, 1921. The contact end comprises a transverse bar 1 on which are mounted two independent contact shoes 2 and 3 adapted to engage the under sides of the trolley wires. Between the adjacent ends of the shoes is an insulating guide bracket 4, while at their outer ends the shoes have extension lugs 5 provided with fender loops 6 and having attached thereto flexible wires 7 and 8 which connect with the terminals of the car motor.

In the trolley switch arrangement shown

in the drawing, the main or through line wires *a* and *b* are assumed to be positive and 50 negative respectively and the branch line wires *c* and *d* are assumed to be negative and positive respectively. In accordance with the present day practice, the main line wires *a* and *b* are uninterrupted at the point of 55 attachment of the switch.

The switch, as shown, is built up of five cross bars 9, 10, 11, 12 and 13 of impregnated wood or other tough insulating material and pairs of flat strips 16, 17 and 16', 60 17' secured edgewise to the under sides of the cross bars near their ends to form guide ways 14 and 15 for the fender loops on the trolley. The ends of the guide strips are bent in opposite directions to form flaring 65 entrances to the guide ways 14 and 15. Across the middle portions of the bars 9, 10 and 11 are two short guide strips 18 and 19. At the centers of bars 11, 12 and 13 is attached a bent guide block or frog piece 20 70 of insulating material, while between it and guide strips 16' and 17' is an insulating block 21.

When the switch is installed the through line wires *a* and *b* extend across beneath the bars 9 to 13 parallel to the guide way 14. The switch is held positioned vertically with the lower edges of the several guide strips in substantially the operative plane of the trolley wires by means of hanger ears 22 80 connecting the wires *a*, *b*, *c* and *d* to the left side bar 9 and the wire *a* to the right hand bar 13. Within the bounds of the switch the several trolley wires are drawn up and secured to the under side of the intermediate 85 cross bars by clips 23.

In order that the trolley head may pass the switch with a minimum impact, the switch is designed to permit the head to pass beneath it and to shift from one pair of 90 trolley wires to the other without changing its elevation. Accordingly the guide strip 17 has secured to its lower edge a short section of trolley wire 24^a which extends out a short distance beyond the outermost cross 95 bar 9 and clipped at 25 to the upper side of

the through trolley wire *a*, so that current will be supplied to either trolley contact shoe 2 or 3 through the short wire section 24^a, during its passage along that side of the switch. Similarly the guide strip 18 carries a short wire section 24^b; the guide strip 19 has a section 24^c, and the guide strip 17 has a section 24^d.

When a trolley approaches the switch 10 from the right, it will be directed by its guide bracket 4 in cooperation with the frog block 20, depending upon whether the vehicle is tending to go straight ahead or veering off to the left. In the first case the 15 bracket 4 will pass to the farther side of the frog 20 and cause the trolley guide loop 6 to enter the guide way 14, and in the other case the guide bracket 4 will pass to the near side of the frog 20 which will cause the 20 opposite loop 6 to enter guide way 15. When the trolley approaches the switch from the left, it is automatically directed by one of the guide loops 6 passing into and along the corresponding guide way 14 or 15.

25 In order that there may be no chance of short-circuiting the trolley wires at the switch, it is necessary to remove one of the wires from the area of possible short-circuiting contact. However, since such removal 30 operates to interrupt the flow of current to the car, it is desirable that the removed section be made as short as possible, since it is necessary to depend upon the momentum of the car to carry it past the dead section. 35 By arranging to have the adjacent wires *b* and *c* of the main and branch lines of like potential, they may be extended well beyond the center of the switch without danger of being short-circuited with wire *a* or *b* by a 40 single contact shoe 2 or 3 coming in contact with both simultaneously.

Between the middle of the switch and the right hand end thereof, there is an area in 45 which a single contact shoe might simultaneously engage the wire section 24^d and the wire *b* which are under different potentials and cause a short-circuit of the system. Accordingly the insulating block 21 is introduced at this point and by reason of its 50 carrying the line wire *b* up out of the contact plane and its bottom edge offering an insulated path for the trolley in that plane the wire *b* for the length of the block is effectually shielded from contact with the trolley. 55 The operative length of the insulating block will, of course, depend upon circumstances, but as a general proposition it is less than half the length of the switch.

The ends of the guide strips 18 and 19 are 60 rounded and the strips 17 and 17' are overrun by the trolley wire sections 24^a and 24^d as shown in the drawing to afford gradual approach thereto of the trolley.

The opposite ends of cross bars 9 and 13 65 are provided with loops 26 whereby the

switch may be suspended in the usual manner by span wires.

While I have shown and described the best form of the invention known to me, I do not desire to be restricted thereto. 70

What I claim as new and desire to secure by Letters Patent of the United States, is:

1. An overhead switch for two wire trolley systems comprising a structure for connecting and supporting main line and 75 branch line wires insulatively and in spaced relation, and means carried by said structure for guiding a double contact trolley in its passage thereof.

2. An overhead switch for two wire 80 trolley systems comprising a structure for connecting and supporting main line and branch line wires insulatively and in spaced relation, means for directing a double contact trolley in its approach to said switch, 85 and means for guiding the trolley in its passage thereof.

3. An overhead switch for two wire trolley systems comprising a structure for connecting and supporting main line and 90 branch line wires insulatively and in spaced relation, means for guiding a double contact trolley in its passage between main line and branch line wires, and means to prevent short-circuiting of wires under difference of 95 potential by said trolley.

4. An overhead switch for two wire trolley systems comprising a structure for connecting and supporting main line and branch line wires insulatively and in spaced 100 relation, means for guiding a double contact trolley in its passage between main and branch line wires, insulator means arranged on one of said main line wires adjacent the point of departure of the branch wires to 105 prevent contact of the trolley therewith.

5. An overhead switch for two wire trolley systems comprising a structure for connecting and supporting main line and branch line wires insulatively and in spaced 110 relation, means for guiding a double contact trolley in its passage of said structure, insulative and conductive contact tracks and surfaces on said structure arranged to permit passage of the trolley without change 115 of its elevation.

6. An overhead switch for two wire trolley systems comprising a structure built up of insulating bars and transverse guide strips, and means for connecting said guide 120 strips to main line and branch line wires.

7. An overhead switch for two wire trolley systems comprising a structure built up of insulating bars, pairs of spaced guide strips traversing all said bars and secured 125 adjacent their ends, intermediate guide strips traversing certain bars at one side of said structure, and insulating blocks traversing certain bars at the opposite side of said structure. 130

8. An overhead switch for two wire trolley systems comprising a structure built up of insulating bars and transverse guide strips, means for attaching main line and branch line wires to said structure above the operative path of the trolley, and wire sections secured to said transverse guide strips in the path of the trolley and adapted at their outer ends to be connected to the main line and branch line wires.
- 10
- In witness whereof, I have hereunto set my hand this 24th day of March, 1922.

GEORGE W. BOWER.
